US00D499092S

(12) **United States Design Patent** (10) Patent No.: **US D499,092 S**
Fan (45) Date of Patent: **** Nov. 30, 2004**

(54) **ELECTRONIC APPLIANCE HOLDING DEVICE**

(76) Inventor: **Eagle Fan**, No. 133, Cheng-Kung 6 St., Chu-Pei City, Hsinchu Hsien (TW)

(**) Term: **14 Years**

(21) Appl. No.: **29/199,418**

(22) Filed: **Feb. 14, 2004**

(51) LOC (7) Cl. **14-03**

(52) U.S. Cl. **D14/253; D14/217; D14/434**

(58) Field of Search **D14/137, 434, D14/138, 447, 148, 147, 149-151, 140-142, 240, 241, 251-253, 451, 218, 217; 379/426, 449, 419, 420.01-420.04, 428.01-428.04, 440, 454, 455, 446; 455/550.1-90.3; D13/107, 108; 224/670, 197, 271; D3/218; 248/221.11, 231.81; 320/110-115**

Primary Examiner—Jeffrey Asch

(57) **CLAIM**

The ornamental design for electronic appliance holding device, as shown and described.

DESCRIPTION

FIG. 1 is a perspective view of electronic appliance holding device showing my new design;

FIG. 2 is a front elevational view thereof;

FIG. 3 is a rear elevational view thereof;

FIG. 4 is a left side elevational view thereof;

FIG. 5 is right side elevational view thereof;

FIG. 6 is a top view thereof;

FIG. 7 is a bottom view thereof; and,

FIG. 8 is a perspective view thereof in an alternate position for use.
